(57) **ABSTRACT**

Provided is a connector having excellent abrasion resistance. The invention applies to a connector including a terminal portion electrically connecting two objects to be connected and a connector housing portion in which the terminal portion is accommodated. The connector housing portion has a first housing in which a fixing portion to which a fixed portion formed in the terminal portion is to be fixed is formed and a second housing that engages with a main body-side housing fixed to one of the objects to be connected in a state in which the first housing is accommodated in the second housing.

CONNECTOR AND ELECTRICAL CONNECTION DEVICE

CROSS-REFERENCE TO RELATED APPLICATION

This application is based upon and claims the benefit of priority from Japanese patent application No. 2015-69074, the entire disclosure of which is hereby incorporated by reference.

BACKGROUND OF THE INVENTION

1. Field of the Invention

The present invention relates to a connector that electrically connects two objects to be connected, and an electrical connection device including this connector.

2. Description of Related Art

For example, JP 2014-010949A discloses an electrical connector such as that shown in FIG. 1 as an electrical connection device that electrically connects two objects to be connected. This electrical connector has a first housing (30) which is fixed to a substrate side and in which male terminals (3, 4) on the substrate side are accommodated as well as a second housing (40) and a third housing (50) in which a female terminal (10) is held and which are fixed to the first housing (30). In this electrical connector, in a state in which the first to third housings (30, 40, 50) are combined together, the male terminals (3, 4) are electrically connected to the female terminal (10).

Incidentally, for example, if the above-described electrical connector vibrates due to an external factor or the like, the female terminal (10) rubs against the second housing (40) and the third housing (50). In that case, the surfaces of the second housing (40) and the third housing (50) are scraped away by the female terminal (10), resulting in the generation of abrasion powder.

SUMMARY OF THE INVENTION

The present invention was made to address the above-described problem, and it is an object thereof to provide a connector and an electrical connection device that have excellent abrasion resistance.

(1) To address the above-described problem, a connector according to an aspect of the invention is a connector including a terminal portion electrically connecting two objects to be connected and a connector housing portion in which the terminal portion is accommodated, the connector housing portion having a first housing in which a fixing portion to which a fixed portion formed in the terminal portion is to be fixed is formed and a second housing that engages with a main body-side housing fixed to one of the objects to be connected in a state in which the first housing is accommodated in the second housing.

With this configuration, the fixed portion formed in the terminal portion is fixed to the fixing portion of the first housing, and thus, for example, even if the connector vibrates due to an external factor or the like, the terminal portion vibrates together with the first housing. Accordingly, with this configuration, vibration of the terminal portion relative to the first housing is prevented, and thus scraping away of the first housing composed of a resin or the like by the terminal portion composed of a metal or the like can be prevented.

Therefore, with this configuration, a connector having excellent abrasion resistance can be provided.

2

(2) It is preferable that a projection serving as the fixed portion is formed in the terminal portion, a hole portion serving as the fixing portion is formed in the first housing, and the terminal portion is fixed to the first housing by the projection being press-fitted into the hole portion.

With this configuration, the terminal portion can be fixed to the first housing by simply press-fitting the projection, which is the fixed portion formed in the terminal portion, into a recess formed in the first housing. That is to say, with this configuration, the terminal portion can be fixed to the first housing using relatively simple shapes.

(3) It is more preferable that a protruding portion protruding outward from a surface of the projection is formed in the projection, the protruding portion protrudes in a direction along a direction in which the terminal portion is inserted and removed, and a leading end portion of the protruding portion abuts against the hole portion. With this configuration, vibration that occurs in the direction in which the connector is inserted and removed can be appropriately prevented.

(4) To address the above-described problem, an electrical connection device according to an aspect of the invention is an electrical connection device including any of the above-described connectors, the connector including a terminal portion and a connector housing portion in which the terminal portion is accommodated and electrically connecting a first object to be connected to a substrate serving as a second object to be connected via the terminal portion, a main body-side contact connected to the substrate, and a main body-side housing fixed to the substrate. With this configuration, an electrical connection device having a connector having excellent abrasion resistance can be provided.

It should be noted that the forgoing and other objects, features, and advantages of the invention will become apparent upon reading the following description with reference to the accompanying drawings.

BRIEF DESCRIPTION OF THE DRAWINGS

40 FIG. 1 is a perspective view schematically showing a connector and an electrical connection device including this connector according to an embodiment of the present invention.

45 FIG. 2A is a rear view of the electrical connection device shown in FIG. 1.

FIG. 2B is a bottom view of the electrical connection device shown in FIG. 1.

50 FIG. 3 is a vertical cross-sectional view of the electrical connection device shown in FIG. 1 and shows a state before the connector is fitted to a main body-side housing.

55 FIG. 4 is a perspective view showing a shape of a main body-side female contact.

FIG. 5A is a perspective view of a core housing.

FIG. 5B is a perspective view of a terminal portion.

55 FIG. 6 is a vertical cross-sectional view of the core housing and shows the core housing together with the terminal portion fixed thereto.

60 FIG. 7 is a perspective view showing a state in which core housings into which respective terminal portions are inserted are accommodated in a connector housing whose upper portion is not shown.

65 FIG. 8A is an explanatory diagram of an assembly process of the connector and shows how one core housing and a corresponding terminal portion are combined with each other.

FIG. 8B is an explanatory diagram of the assembly process of the connector and shows how the core housing

and the terminal portion that have been combined with each other are inserted into the connector housing.

FIG. 9A is an explanatory diagram of an operation for fitting the connector to the main body-side housing and shows a state in which the connector is pressed down to a position that is nearest to a substrate.

FIG. 9B is an explanatory diagram of the operation for fitting the connector to the main body-side housing and shows a state in which fitting of the connector into the main body-side housing is complete.

FIG. 10 is a vertical cross-sectional view of the electrical connection device shown in FIG. 1 taken along a plane different from that of FIG. 3 and shows the state in which the connector is pressed down to the position that is nearest to the substrate.

DETAILED DESCRIPTION OF THE INVENTION

Hereinafter, embodiments of the present invention will be described with reference to the drawings. The present invention is widely applicable to a connector that electrically connects two objects to be connected and an electrical connection device including this connector.

Configuration

FIG. 1 is a perspective view schematically showing a connector 20 and an electrical connection device 1 including this connector 20 according to an embodiment of the present invention. FIG. 2A is a rear view of the electrical connection device 1 shown in FIG. 1, and FIG. 2B is a bottom view of the electrical connection device 1 shown in FIG. 1. FIG. 3 is a vertical cross-sectional view of the electrical connection device 1 shown in FIG. 1 and shows a state before the connector 20 is fitted to a main body-side housing 10. The electrical connection device 1 according to the present embodiment may be used in automobiles, for example, in order to electrically connect a busbar (not shown) to a substrate 50 of a device (not shown) to which power is supplied from the busbar. It should be noted that in the drawings, for convenience of description, the direction indicated by the arrow denoted by "Front" is referred to as "front side" or "forward", the direction indicated by the arrow denoted by "Rear" is referred to as "rear side" or "rearward", the direction indicated by the arrow denoted by "Right" is referred to as "right side", the direction indicated by the arrow denoted by "Left" is referred to as "left side", the direction indicated by the arrow denoted by "Up" is referred to as "upper side" or "upward", and the direction indicated by the arrow denoted by "Down" is referred to as "lower side" or "downward". The up-down direction corresponds to the direction in which the connector 20 is inserted and removed.

The electrical connection device 1 includes main body-side male contacts 2, the main body-side housing 10, reinforcing tabs 3, main body-side female contacts 4, the connector 20, and the like.

Each of the main body-side male contacts 2 is a conductive member formed in the shape of a pin, and is fixed to the busbar. The main body-side male contacts 2 thus have the same potential as the busbar. It should be noted that although each main body-side male contact 2 is formed in the shape of a pin in the present embodiment, the main body-side male contacts 2 are not limited to a pin shape and may have any shape as long as they are formed as contacts of a so-called male type. For example, the main body-side male contacts 2 may also each be formed by bending a narrow strip of sheet metal into a rod shape.

The main body-side housing 10 is a resin member formed in a substantially rectangular tube shape extending in the up-down direction. When viewed from above, the main body-side housing 10 is formed in a rectangular shape that is elongated in the left-right direction. Specifically, the main body-side housing 10 has a front wall portion 11, a rear wall portion 12, a right wall portion 13, and a left wall portion 14, and these wall portions are formed as a single member having the substantially rectangular tube shape.

10 A step portion 15 is formed in a lower portion of the rear wall portion 12 of the main body-side housing 10, the step portion 15 being formed in a step shape protruding rearward from that lower portion. Also, slit portions 16 passing through the main body-side housing 10 in the up-down direction are formed on both the left and right sides of the main body-side housing 10.

Also, two coil spring accommodating portions 17a and 17b are formed in the main body-side housing 10. Specifically, one coil spring accommodating portion 17a is formed 20 by a groove-shaped cut-out portion in a lower portion of a corner portion between the rear wall portion 12 and the right wall portion 13. The other coil spring accommodating portion 17b is formed by a groove-shaped cut-out portion in a lower portion of a corner portion between the rear wall 25 portion 12 and the left wall portion 14. Coil springs 5a and 5b are placed extending in the up-down direction within the respective coil spring accommodating portions 17a and 17b.

Also, a main body-side engaging claw 18 is formed on the main body-side housing 10. Specifically, the main body-side 30 engaging claw 18 is formed in a middle portion of the rear wall portion 12 with respect to the left-right direction and located slightly above the step portion 15. The main body-side engaging claw 18 is formed projecting rearward from the rear wall portion 12. The main body-side engaging claw 35 18 is engageable with a connector-side engaging claw 23 of a connector housing 21, which will be described in detail later.

The reinforcing tabs 3 are each formed by bending a portion of a metal plate-shaped member. Each reinforcing tab 3 is provided in such a manner that in a state in which the reinforcing tab 3 is inserted into and fixed in the corresponding slit portion 16 of the main body-side housing 10, a flat bent portion 3a that is bent as described above faces downward. The reinforcing tabs 3 are respectively press-fitted into and fixed in the two slit portions 16.

The main body-side housing 10 is fixed to the substrate 50 by the bent portions 3a of the reinforcing tabs 3, which are fixed to the main body-side housing 10 in the above-described manner, being soldered to the substrate 50.

50 FIG. 4 is a perspective view showing the shape of a single main body-side female contact 4. Each main body-side female contact 4 is formed in a shape such as that shown in FIG. 4 by bending a metal sheet formed through press punching, for example. The main body-side female contact 55 4 has a rectangular tube portion 4a formed in a rectangular tube shape and a soldered portion 4b, and these portions are formed as a single member. A spring portion 4c is formed inside the rectangular tube portion 4a. The spring portion 4c holds a connector-side male contact 31 (described in detail later) inserted into the rectangular tube portion 4a between the rectangular tube portion 4a and the spring portion 4c. In the present embodiment, five main body-side female contacts 4 are arranged in a line in the left-right direction and accommodated in the main body-side housing 10 fixed to the substrate 50 in a state in which the soldered portions 4b of the respective main body-side female contacts 4 are soldered to the substrate 50. In this state, an upper opening of each

main body-side female contact 4 is exposed upward through an upper opening of the main body-side housing 10. Configuration of Connector

FIG. 5A is a perspective view of a core housing 25. FIG. 5B is a perspective view of a terminal portion 30. FIG. 6 is a vertical cross-sectional view of the core housing 25 and shows the core housing 25 together with the terminal portion 30 in a state in which it is fixed to the core housing 25. FIG. 7 is a perspective view showing a state in which core housings 25 into which respective terminal portions 30 are inserted are accommodated in the connector housing 21 whose upper portion is not shown.

The connector 20 has the connector housing 21 (second housing), the core housings 25 (first housing), and the terminal portions 30, and is formed by assembling these members together. In the present embodiment, a connector housing portion 20a is constituted by the connector housing 21 and the core housings 25.

Referring to FIGS. 1 to 3, the connector housing 21 may be a member formed by resin molding, for example. The core housings 25 and the terminal portions 30 are inserted into the connector housing 21 from an opening side, the opening being formed on the lower side of the connector housing 21, and thus the core housings 25 and the terminal portions 30 are accommodated inside the connector housing 21.

A cantilevered claw portion 22 is formed in a rear portion of the connector housing 21, the cantilevered claw portion 22 having the connector-side engaging claw 23 that is engageable with the main body-side engaging claw 18, which is formed on the rear wall portion 12 of the main body-side housing 10. The connector-side engaging claw 23 is formed projecting forward from a lower front portion of the claw portion 22. The claw portion 22 is formed such that its lower portion can bend in the front-rear direction with its upper portion serving as a base end portion.

Moreover, four partition walls 24 that partition an inner space of the connector housing 21 into five spaces S are formed inside the connector housing 21 (see FIG. 8B). The partition walls 24 are each formed extending in the front-rear direction and the up-down direction and are arranged in the left-right direction at regular intervals. One core housing 25 and a corresponding terminal portion 30 that are combined with each other are inserted into each of the five spaces S demarcated by these partition walls 24, as will be described in detail later.

Each core housing 25 may be a member that is made of a resin material, for example, and that is formed in a substantially rectangular tube shape extending in the up-down direction as shown in FIGS. 5A and 6. A first protruding portion 26 is formed in an upper portion of a front wall portion of the core housing 25, the first protruding portion 26 protruding outward (forward) in such a manner as to form a step. Furthermore, a second protruding portion 27 is formed at a central portion of the first protruding portion 26 with respect to the up-down direction, the second protruding portion 27 protruding in the same direction as the first protruding portion 26 in such a manner as to form a step. Moreover, a first opening 28 is formed in an upper portion of a rear wall portion of the core housing 25, the first opening 28 opening rearward. Furthermore, a cut-out portion 29 is formed in upper portions of both left and right wall portions of the core housing 25, the cut-out portion 29 being cut out from the rear side toward the front side. Moreover, a hole portion 27a (fixing portion) is formed in the second protruding portion 27, the hole portion 27a being formed by a through hole passing through the second protruding por-

tion 27 in the front-rear direction. The hole portion 27a is formed such that its inner circumferential surface has a rectangular shape when viewed in the front-rear direction.

Each terminal portion 30 is formed in a shape such as that shown in FIG. 5B by bending a metal sheet formed through press punching, for example. Each terminal portion 30 has a male contact 31 (connector-side male contact), a female contact 35 (connector-side female contact), and a joint portion 40, and these portions are formed as a single member.

The male contact 31 is constituted by a contact portion 32. As shown in FIG. 5B, the contact portion 32 is formed by folding a plate-shaped portion along a fold line extending in the up-down direction. The contact portion 32 is thus formed in a substantially rod-like shape elongated in the up-down direction and having a predetermined thickness.

The female contact 35 is constituted by a contact portion 36 having a rectangular tube portion 36a and a spring portion 36b. The rectangular tube portion 36a is formed in a rectangular tube shape extending in the up-down direction. The spring portion 36b is formed inside the rectangular tube portion 36a. In the female contact 35, when the main body-side male contact 2 is inserted into the rectangular tube portion 36a, the main body-side male contact 2 is held between an inner portion of the rectangular tube portion 36a and the spring portion 36b. Moreover, a projecting piece 37 (fixed portion, projection) is formed integrally with the female contact 35. The projecting piece 37 is formed projecting forward from a central portion of the female contact 35 with respect to the up-down direction. A protruding portion 37a protruding upward is formed in a leading end portion of the projecting piece 37. In the present embodiment, the protruding portion 37a protrudes in a direction (up-down direction) along the direction in which the terminal portion 30 is inserted and removed (i.e., the direction in which the connector 20 is inserted and removed).

Since the male contact 31 has a relatively simple shape as is described above, the overall size of the male contact 31 is slightly smaller than that of the female contact 35, which has a more complicated shape than the male contact 31.

The joint portion 40 has a first straight line portion 41, a second straight line portion 42, and a connecting portion 43, which are formed as a single portion having a U shape.

The first straight line portion 41 is a straight line-shaped portion that is formed extending in the up-down direction, and is continuous with the male contact 31 on one end side (lower side). A wide portion 41a is formed in a central portion of the first straight line portion 41 with respect to the up-down direction, the wide portion 41a being wider than the first straight line portion 41 in the left-right direction.

The second straight line portion 42 is a straight line-shaped portion that is formed extending in the up-down direction, and is continuous with the female contact 35 on one end side (lower side). The second straight line portion 42 is provided extending parallel to the first straight line portion 41. Moreover, the second straight line portion 42 is slightly shorter than the first straight line portion 41 in the up-down direction.

The connecting portion 43 is provided extending in a direction that is orthogonal to the first straight line portion 41 and the second straight line portion 42, and connects an upper end portion of the first straight line portion 41 and an upper end portion of the second straight line portion 42 to each other. Both end portions of the connecting portion 43 are provided as curved portions 43a that are each formed to have a circular arc shape. Thus, even if an external force is

exerted on the terminal portion 30, the concentration of stress on a connection area between the first straight line portion 41 and the connecting portion 43 and a connection area between the second straight line portion 42 and the connecting portion 43 can be avoided.

Assembly Process of Connector

FIG. 8A is an explanatory diagram of an assembly process of the connector 20 and shows how one core housing 25 and a corresponding terminal portion 30 are combined with each other. FIG. 8B is an explanatory diagram of the assembly process of the connector 20 and shows how the core housing 25 and the terminal portion 30 that have been combined with each other are inserted into the connector housing 21. It should be noted that the shape of an upper portion of the connector housing 21 in FIG. 8B is shown schematically.

During assembly of the connector 20, first, the core housing 25 and the terminal portion 30 are combined with each other as shown in FIG. 8A. Specifically, the female contact 35 is inserted into the core housing 25 from the first opening 28 side such that the projecting piece 37 of the female contact 35 is accommodated in the second protruding portion 27 of the core housing 25. Thus, the projecting piece 37 and the protruding portion 37a are press-fitted into the second protruding portion 27, and therefore unintentional disengagement of the terminal portion 30 from the core housing 25 can be prevented. More specifically, referring to FIG. 6, a lower portion of the projecting piece 37 and the protruding portion 37a are held between an upper surface and a lower surface of the inner circumferential surface of the hole portion 27a formed inside the second protruding portion 27, and therefore unintentional disengagement of the terminal portion 30 from the core housing 25 can be prevented. Thus, the terminal portion 30 can be fixed to the core housing 25. Moreover, at this time, the contact portion 32 of the male contact 31 and the contact portion 36 of the female contact 35 are arranged so as to face downward. It should be noted that in the state in which the core housing 25 and the terminal portion 30 are combined with each other in the above-described manner, the wide portion 41a is placed on top of the cut-out portion 29 of the core housing 25. In the present embodiment, five terminal portions 30 are respectively combined with five core housings 25.

Next, the above-described core housing 25 to which the corresponding terminal portion 30 is attached is inserted into the connector housing 21. Specifically, the core housing 25 is inserted into the corresponding space S (see FIG. 8B) demarcated by the partition walls 24 such that a second opening 25a of the core housing 25 faces downward. At this time, the core housing 25 is inserted into the connector housing 21 until the second protruding portion 27 is inserted into a slit 21a (see FIG. 3) that is formed in the front wall portion of the connector housing 21. Thus, unintentional disengagement of the core housing 25 from the connector housing 21 is prevented. The core housings 25 to which the respective terminal portions 30 are attached are fixed to the connector housing 21 in the above-described manner, and thus assembly of the connector 20 is complete.

Fitting of Connector to Main Body-Side Housing

FIG. 9A is an explanatory diagram of an operation for fitting the connector 20 to the main body-side housing 10 and shows a state in which the connector 20 is pressed down to a position that is nearest to the substrate 50. FIG. 9B is an explanatory diagram of the operation for fitting the connector 20 to the main body-side housing 10 and shows a state in which fitting of the connector 20 to the main body-side housing 10 is complete. Hereinafter, the operation for fitting

the connector 20 to the main body-side housing 10 will be described with reference to FIGS. 3, 9A, and 9B.

In the state in FIG. 3, that is to say, in the state before the connector 20 is fitted to the main body-side housing 10, the main body-side contacts (male contacts 2 and female contacts 4) are not in contact with the connector-side contacts (female contacts 35 and male contacts 31), and therefore the busbar and the device having the substrate 50 are not electrically connected to each other. In this state, when the connector 20 is pressed down toward the substrate 50, the connector 20 moves to the main body-side housing 10 side. Accordingly, the female contacts 35 on the connector 20 side move to the male contact 2 side, and the male contacts 2 are thus inserted into the female contacts 35. Meanwhile, the male contacts 31 on the connector 20 side are inserted into the female contacts 4. As a result, the male contacts 2 are electrically connected to the female contacts 35, and the male contacts 31 are also electrically connected to the female contacts 4. Thus, the busbar and the device having the substrate 50 can be electrically connected to each other.

When the connector 20 is pressed down toward the substrate 50 as described above, a rear portion of the connector housing 21 abuts against the coil springs 5a and 5b. When the connector 20 is further pressed down toward the substrate 50 against the biasing force of the coil springs 5a and 5b, the connector 20 moves further to the main body-side housing 10 side.

Moreover, as the connector 20 is pressed down toward the substrate 50 against the biasing force of the coil springs 5a and 5b as described above, the connector-side engaging claw 23 passes over the main body-side engaging claw 18 with a leading end portion of the claw portion 22 of the connector 20 bending rearward. As a result, the connector-side engaging claw 23 becomes located below the main body-side engaging claw 18 (see FIG. 9A). It should be noted that FIG. 10 is a cross-sectional view of the electrical connection device 1 when viewed from the rear side and shows the state in which the connector 20 is pressed down to the position that is nearest to the substrate 50.

In the state in which the connector 20 is pressed down to the position that is nearest to the substrate 50 as described above, if the pressing force on the connector 20 toward the substrate 50 is released, the biasing force of the coil springs 5a and 5b pushes the connector 20 upward, bringing the connector-side engaging claw 23 and the main body-side engaging claw 18 into close contact with each other in the up-down direction. Thus, the connector 20 can be fitted to the main body-side housing 10 without looseness of the connector housing 21 with respect to the main body-side housing 10.

Vibration Resistance of Connector

As described above, the electrical connection device 1 according to the present invention may be used in automobiles, for example, and therefore may be used in an environment that is relatively often exposed to vibrations. Furthermore, in the present embodiment, the busbar, which is a first object to be connected, and the device, which is a second object to be connected, are provided separately from each other and thus vibrate in different vibration modes. In this case, it can be conceived that, for example, when a component (e.g., main body-side male contact 2) fixed to the busbar side and a component (e.g., main body-side housing 10) fixed to the substrate 50 side rub against each other, or a component (e.g., main body-side housing 10) fixed to the substrate 50 side and a portion (e.g., male contact 31) fixed to the connector 20 side rub against each other, the components may be significantly abraded.

However, in the connector 20 according to the present embodiment, the male contact 31 is formed on one side of each terminal portion 30. Thus the length of the joint portion 40 can be increased, the joint portion 40 joining the contacts 31 and 35 formed in opposite end portions of the terminal portion 30. More specifically, since the male contact 31 has a simplified configuration and a small size when compared with the female contact 35, the end portion (lower end portion of the first straight line portion 41) of the joint portion 40 on the male contact 31 side can be formed so as to be extended to the male contact 31 side. Thus, the length of the joint portion can be longer when compared with the case where female contacts are formed on both end sides of the terminal portion, for example. Consequently, even if the two objects to be connected (the busbar and the device having the substrate 50 in the case of the present embodiment) vibrate independently of each other, the vibrations can be absorbed by the joint portion 40 having a secured sufficient length.

Abrasion Resistance of Connector

In the electrical connection device 1 according to the present embodiment, for example, if the main body-side male contacts 2 fixed to the busbar side or the female contacts 4 fixed to the substrate 50 side vibrate, the terminal portions 30 that are in contact with those contacts also vibrate. In that case, it can be conceived that the terminal portions 30 will rub against the core housings 25, and thus the core housings 25 will be scraped away by the terminal portions 30, resulting in the generation of abrasion powder.

However, in the connector 20 according to the present embodiment, the housing has a two-piece structure (the core housings 25 and the connector housing 21), and the terminal portions 30 are fixed to the respective core housings 25. Thus, the terminal portions 30 vibrate together with the core housings 25. As a result, the core housings 25 vibrate relative to the connector housing 21. Here, the core housings 25 are composed of a resin, and the connector housing 21 is also composed of a resin. Since resins do not generate much abrasion powder when rubbing against each other, not much abrasion powder is generated by the core housings 25 vibrating relative to the connector housing 21.

Effects

As described above, in the connector 20 according to the present embodiment, the projecting piece 37, which is the fixed portion formed in each terminal portion 30, is fixed to the hole portion 27a, which is the fixing portion of each core housing 25. Thus, for example, even if the connector 20 vibrates due to an external factor or the like, the terminal portion 30 vibrates together with the core housing 25. Accordingly, with the connector 20, vibration of the terminal portions 30 relative to the core housing 25 is prevented, and therefore the scraping away of the core housings 25, which are composed of a resin, by the terminal portions 30, which are composed of a metal can be prevented.

Moreover, with the connector 20, each terminal portion 30 can be fixed to the corresponding core housing 25 by simply press-fitting the projection (projecting piece 37), which is the fixed portion formed in the terminal portion 30, into the hole portion 27a, which is formed in the core housing 25. That is to say, with this configuration, the terminal portion 30 can be fixed to the core housing 25 using relatively simple shapes.

Moreover, with the connector 20, the protruding portion 37a protruding in the direction (up-down direction in FIGS. 6, 9A, and 9B) along the direction in which the terminal portion 30 is inserted and removed is formed in the projecting piece 37. In addition, in a state in which the terminal

portion 30 is fixed to the core housing 25, a leading end portion of the protruding portion 37a abuts against the hole portion 27a. Thus, with the connector 20, vibration that occurs in the direction in which the connector 20 is inserted and removed can be appropriately prevented.

Moreover, with the electrical connection device 1 according to the present embodiment, an electrical connection device having the connector 20, which has excellent abrasion resistance, can be provided.

Although an embodiment of the present invention has been described above, the present invention is not limited to the foregoing description, and various changes can be made thereto without departing from the gist of the present invention.

Modification

(1) In the foregoing embodiment, the projecting piece 37 having the shape of a projection is described as an example of the fixed portion formed in the terminal portion 30, and the hole portion 27a is described as an example of the fixing

portion formed in the core housing 25. However, the present invention is not limited to this configuration. Specifically, the fixing portion and the fixed portion may take any shape that enables fixation of the terminal portion to the core housing.

The present invention is widely applicable as a connector that electrically connects two objects to be connected and an electrical connection device including this connector. The present invention is not limited to the above embodiment, and all modifications, applications, and equivalents thereof that fall within the claims, for which modifications and applications would become naturally apparent by reading and understanding the present specification, are intended to be embraced in the claims.

What is claimed is:

1. A connector comprising a terminal portion electrically connecting two objects to be connected and a connector housing portion in which the terminal portion is accommodated,

the connector housing portion having:

a first housing in which a fixing portion is formed, a fixed portion is formed in the terminal portion, and the fixed portion is fixed to the fixing portion; and

a second housing that engages with a main body-side housing fixed to one of the objects to be connected in a state in which the first housing is accommodated in the second housing,

wherein the terminal portion is not contacting the second housing, wherein the first housing has a first end, wherein the first end receives the fixed portion of the terminal portion and faces inward into the second housing,

wherein a projection serving as the fixed portion is formed in the terminal portion, a hole portion serving as the fixing portion is formed in the first housing, and the terminal portion is fixed to the first housing by the projection being press-fitted into the hole portion,

wherein the terminal portion includes a contact portion extending along a direction in which the terminal portion is inserted and removed, and configured to be accommodated in the first housing, the projection protrudes from the contact portion to a direction perpendicular to the direction in which the terminal portion is inserted and removed, and the hole portion of the first housing is extending along the direction perpendicular to the direction in which the terminal portion is inserted and removed, and into which the projection is press-fitted.

11

2. The connector according to claim 1,
wherein a protruding portion protruding outward from a
surface of the projection is formed in the projection,
and
the protruding portion protrudes in a direction along a 5
direction in which the terminal portion is inserted and
removed, and a leading end portion of the protruding
portion abuts against the hole portion.

3. An electrical connection device comprising:
the connector according to claim 1, the connector includ- 10
ing a terminal portion and a connector housing portion
in which the terminal portion is accommodated and
electrically connecting a first object to be connected to
a substrate serving as a second object to be connected
via the terminal portion; 15
a main body-side contact connected to the substrate; and
a main body-side housing fixed to the substrate.
